UNITED STATES PATENT OFFICE.

JULIUS MALTBY, OF WATERBURY, CONNECTICUT, ASSIGNOR TO WATERBURY BUCKLE CO., OF WATERBURY, CONNECTICUT, A CORPORATION.

SLIDE BUCKLE.

Application filed November 5, 1923. Serial No. 672,769.

To all whom it may concern:

Be it known that I, JULIUS MALTBY, a citizen of the United States, residing at Waterbury, in the county of New Haven 5 and State of Connecticut, have invented a new and useful Improvement in Slide Buckles; and I do hereby declare the following, when taken in connection with the accompanying drawings, and the characters of 10 reference marked thereon, to be a full, clear, and exact description of the same, and which said drawings constitute part of this application, and represent in

Fig. 1 a view in front elevation of a 15 slide-buckle constructed in accordance with my invention.

Fig. 2 a view looking toward the lower edge thereof.

Fig. 3 an edge view thereof.

20 Fig. 4 a view of the slide-buckle in vertical, central section, showing it as webbed.

Fig. 5 a view corresponding to Fig. 3, but showing a modified form of the buckle-frame.

25 My invention relates to an improved slide-buckle designed with particular reference to be used on the non-elastic straps of abdominal supporters, though not so limited, the object being to provide a simple, strong, 30 convenient and highly efficient buckle of the character described, in which the straps are held by the combined action of deflection and friction, rather than by prongs piercing them, and in which provision is made for 35 neutralizing the tendency of the straps to slip when the tension upon them is entirely or measurably removed.

With these ends in view, my invention 40 consists in a slide-buckle having certain details of construction as will be hereinafter described and pointed out in the claim.

In carrying out my invention, as herein shown, I employ a substantially rectangular, sheet-metal buckle-frame having a webbing-opening 6, a lower gripping-bar 7, parallel side-bars 8, and, along its upper side, an offset 9, containing a long, narrow suspension-slot 10, designed for the reception of a short strap (not shown) by means of which 45 the buckle is attached to the garment. Under my invention, the lower edge of the buckle-frame is formed with an integral,

supplemental, loop-like offset 11, the ends of which are shown as merging into the ends of its lower bar 7 though this is not essential. The said loop 11, however produced, encloses an anchoring-slot 12, designed to receive the free end 13 of the strap 14, after the same has been threaded through the buckle and passed around the slide 15 thereof, as shown in Fig. 4, this slide being of any approved construction and provided, as usual, at its respective ends with fingers 16 loosely embracing the side-bars 8 of the buckle-frame upon which the slide is free to move within the limits set by the length of the said bars. Without the anchoring-slot 12, the slide 15 will grip and hold the strap 14 when the same is under draft, but when draft is removed or slackened, the tendency of the strap is to slip. This tendency, however, will be neutralized and practically overcome, if the end 13 of the strap is passed from rear to front, through the slot 12 and then over, in front of, the loop 11, as shown in Fig. 4. In Figs. 1 to 4 inclusive, the offset 11, containing the slot 12, is set back of the plane of the slide, but this is not essential, as evidenced by the modified construction shown by Fig. 5, in which the offset 11 is located in the plane of the buckle-frame.

I claim:

As a new article of manufacture, a slide-buckle comprising a sheet-metal buckle-frame and a sheet-metal slide having sliding movement thereupon, the said frame being formed with a suspension-slot located at its upper end for the reception of the strap by means of which the buckle is fastened to a garment, with a webbing-opening located directly below the said slot, with a gripping-bar forming the lower boundary of the said opening, with side-bars flanking the ends of the said opening and with an anchoring-slot located below the said gripping-bar, and the said slide being narrower than the width of the said opening and bent at its respective ends to loosely embrace the side-bars of the frame, whereby, by passing the end of the strap from rear to front, through the webbing-opening over the upper edge of the said slide, then down in front of the same and

from front to rear through the webbing-opening between the lower edge of the slide and the said gripping-bar and then from rear to front through the said anchoring-slot, the tendency of the webbing to slip when tension upon it is entirely or measurably removed, is neutralized.

In testimony whereof, I have signed this specification in the presence of two subscribing witnesses.

JULIUS MALTBY.
